US00D819684S

(12) **United States Design Patent** (10) Patent No.: **US D819,684 S**
(45) Date of Patent: ** Jun. 5, 2018

(54) **DISPLAY SCREEN WITH GRAPHICAL USER INTERFACE**

(71) Applicant: **Microsoft Corporation**, Redmond, WA (US)

(72) Inventor: **Anthony Neil Dart**, Sammamish, WA (US)

(73) Assignee: **Microsoft Corporation**, Redmond, WA (US)

(**) Term: **15 Years**

(21) Appl. No.: **29/583,356**

(22) Filed: **Nov. 4, 2016**

(51) LOC (11) Cl. **14-04**

(52) U.S. Cl.

USPC **D14/488**; D14/487

(58) **Field of Classification Search**

(57) **CLAIM**

The ornamental design for a display screen with graphical user interface, as shown and described.

DESCRIPTION

The FIGURE is a front view of a display screen with graphical user interface showing my new design.

The broken line showing of the remainder of the display screen forms no part of the claimed design.

1 Claim, 1 Drawing Sheet
